UNITED STATES PATENT OFFICE.

WILLIAM H. GRINDLEY, OF CONGLETON, ENGLAND, ASSIGNOR TO WILLIAM S. PITCIARN, OF NEW YORK, N. Y.

DESIGN FOR A DISH.

SPECIFICATION forming part of Design No. 31,740, dated October 31, 1899.

Application filed September 29, 1899. Serial No. 732,115. Term of patent 3½ years.

To all whom it may concern:

Be it known that I, WILLIAM H. GRINDLEY, a subject of the Queen of Great Britain, residing at Congleton, county of Chester, England, have invented a new and original Design for a Dish; and I do declare the following to be a full, clear, and exact description of the same, reference being had to the accompanying drawings, forming part hereof.

10 In the drawings, Figure 1 is a plan view, and Fig. 2 is a vertical central section and partial side elevation, of a dish embodying my design.

The leading features of my design are as follows: The rim of the dish is scalloped, a flat curved scallop alternating with two rounder or smaller scallops. The center of the dish is depressed, the depression being bounded by a continuous curve, which is provided with an 15 embossed ornamentation consisting of a series

20 of short convex scallops *a*, within which are radial lines *b*, terminating at the boundary of the depression. The rim of the dish is ornamented at its outer edge by a continuous band of embossed beads *c*. Within this band and 25 separated from it by an embossed line essentially parallel to the outer edge of the dish is a row of embossed ornamentations alternately arranged, one ornamentation being a star-like figure *d* and the other a branch-like figure *e*. 30

What I claim is—

The design for a dish substantially as shown and described.

In testimony whereof I have signed this specification, this 19th day of September, 1899, 35 in the presence of two witnesses.

WILLIAM H. GRINDLEY.

Witnesses:

JOHN H. COPESTAKE,
THOMAS W. GALLIMORE.
